UNITED STATES PATENT OFFICE.

RAYMOND N. EHRHART, OF EDGEWOOD, PENNSYLVANIA, ASSIGNOR TO ELLIOTT COMPANY, OF PITTSBURGH, PENNSYLVANIA, A CORPORATION OF PENNSYLVANIA.

CONDENSER CONTROL.

Application filed June 30, 1922. Serial No. 572,106.

The present invention relates broadly to condensers, and more particularly to automatically operable means for shutting off or restricting the supply of condensing water 5 to the condenser under predetermined conditions.

It has heretofore been proposed, as illustrated, for example, in the prior Patent No. 1,395,265 of Nov. 1, 1921, to Powell and myself, to shut off the supply of water to a condenser by means of changes in the vacuum within the condenser. In the construction disclosed in this patent, however, the means for shutting off the supply of water 15 is directly controlled by a vacuum breaker and is of such nature that the supply of water is immediately shut off and must thereafter be manually directed to the condenser. This instantaneous cutting off is objectionable due to the water hammer produced in the pipes supplying the condenser water to the condenser. This condition is considerably increased where the supply of water is such as to afford a considerable head. 20 Furthermore, the manual resetting operation has not been altogether satisfactory.

It has also heretofore been proposed to cut off the supply of water to a condenser by destroying the vacuum therein. In such 30 cases, however, as distinguished from shutting off the supply of water, it has been necessary to always draw water from a supply so located that there is no appreciable head. Even under such conditions, however, 35 the afterflow into the condenser has frequently been such as to produce injury, by flooding or otherwise, to the apparatus served by the condenser.

By the present invention there is provided 40 an improved condenser control effectively obviating the objections to apparatus as heretofore utilized and controlling automatically the supply of water to the condenser in such manner as to make a manual resetting unnecessary and positively prevent injury to 45 any of the apparatus associated with the condenser.

In the accompanying drawings I have shown, for purposes of illustration only, certain embodiments of the present invention, it being understood that the drawings do 50 not define the limits of my invention, as changes may obviously be made in the construction and operation without departing

from the spirit of my invention or scope of my broader claims.

In the drawings,—

Figure 1 is a diagrammatic view, partly broken away, illustrating one method of installing my improved control; 60

Figure 2 is a view on an enlarged scale, of a portion of the construction illustrated in Figure 1; and

Figure 3 is a detail view on an enlarged scale, of a slightly modified form of apparatus. 65

It will be apparent to those skilled in the art that where condensing water is supplied to a condenser under a considerable head, there is considerable danger of flooding the 70 condenser in the event that the water pumps associated therewith do not function properly. This danger is considerably increased where the water is supplied through a comparatively long pipe due to the momentum 75 of the moving body of the water therein. Unless some means is provided for positively shutting off this supply of water, as distinguished merely from cutting off the supply, it is quite possible for the water to flood 80 the condenser and work its way into the engine, turbine or other apparatus associated therewith and cause considerable damage thereto.

In the drawings I have illustrated a condenser 2 adapted to receive a supply of condensing water from any desired source 3, which may or may not provide an effective head. This condensing water may be conducted to the condenser through a suitable 90 pipe line 4 communicating with a header 5 adapted to discharge the water into the condenser through suitable nozzles 6 to provide an effective condensing spray. There is 95 preferably provided at some suitable point in the line 4 a manually operable valve 7 by means of which the excess pressure under which the water is supplied may be largely dissipated.

The condensing water is adapted to be removed from the condenser 2 by means of a pump 8 of any desired construction, as is customary in the art, and the condenser may have a vacuum maintained therein in any usual manner. The condenser is also preferably provided with any well known form of vacuum breaker 9 whereby when the liquid level within the condenser rises beyond 100

a predetermined point the vacuum breaker will be operated to admit air thereto, as will be apparent. This means in itself is sufficient in some cases where the water is not supplied under head, for effecting a cessation of flow of condensing water thereto, but even in such cases there is usually an objectionable afterflow which is frequently sufficient to cause serious damage.

- 10 Cooperating with the vacuum breaker there may, in accordance with the present invention, be provided within the line 4 a controlling valve 10 adapted to be normally urged into the position illustrated in dotted 15 lines in Figure 2, by means of a compression spring 11 surrounding the piston rod 12 which slides through a stationary abutment 13 and which has an operating connection 14 with the valve. Secured to the piston rod 20 12 is a piston 15 operable within a cylinder 16 which is subjected to atmospheric pressure on one side. The opposite side of the piston is subjected to the pressure prevailing in the pipe 4 adjacent the outlet of the 25 valve 10, by means of a suitable connection 17. This connection is preferably of comparatively small cross sectional area whereby the piston 15 will be gradually subjected to pressure variations within the pipe 4.
- 30 In condenser installations of this character, there are usually provided distributing devices within the condensers which absorb a certain amount of pressure. For this reason, the absolute pressure at the outlet of the 35 valve 10 will ordinarily be somewhat greater than that existing within the condenser. It may be assumed, for example, that there is a pressure of one pound absolute within the condenser, a pressure of three pounds absolute at the outlet 40 of the valve, and an atmospheric pressure of fifteen pounds absolute. Under these conditions, there will exist an effective pressure of 12 pounds absolute tending to move the piston into the position illustrated in 45 Figure 2 and thereby maintain the valve 10 in open position. If for any reason the vacuum within the condenser changes, there will be a corresponding change in the absolute 50 pressure existing at the outlet of the valve 10. If the pressure within the condenser should, for example, approximate atmospheric pressure, the pressure at the outlet of the valve 10 would be slightly above this, 55 so that the spring 11 would then draw the piston to the right as viewed in Figure 2 and close the valve 10. In this manner, the supply of condensing water to the condenser 60 would be positively shut off.
- 65 It will be apparent that the rapidity with which the valve 10 closes may be varied by properly proportioning the cross sectional area of the connection 17. By making this connection sufficiently small, it is possible to close the valve 10 gradually enough to pre-

vent any water hammer within the line 4. This has heretofore not been possible with constructions such as shown in the prior patent, and it has been necessary to provide large relief valves on the injection line 70 immediately ahead of the shut off valve. The construction herein disclosed is also such that as soon as the proper conditions are reestablished within the condenser the piston 15 will again be automatically operable to move 75 the valve 10 to open or partially open position. It will be apparent that for this reason the present construction is entirely automatic and is effective for either completely 80 shutting off or restricting the supply of condensing water in accordance with variations in the pressure existing at the outlet of the valve, these pressures being indirectly the result of pressure variations within the condenser.

In Figure 3 there is illustrated a slightly modified embodiment of the present invention. For sake of conciseness in the description, I have designated parts in this figure corresponding to parts already described, 90 with the same reference characters having a prime affixed thereto. With this construction, instead of having the cylinder 16' formed with one end entirely open to the atmosphere, I may provide a closure 18 therefor having a comparatively small bleed opening 19. In this manner the movement of the piston 15' in a direction effective for closing the valve 10' slowly forces out the air that is trapped within the cylinder, thereby forming a dash-pot limiting the rapidity of closing of the valve.

By means of the springs 11 and 11' it is possible to adjust the valve whereby the pistons 15 and 15' will be operated as soon as a 105 predetermined pressure is reached at the outlet of the valve or, correspondingly, the water inlet to the condenser. This is of advantage inasmuch as different condensers may have different resistances to flow in the 110 distributing means provided therefor, thereby making it desirable to be able to adjust the valve to respond to various predetermined pressures. This adjustment with the constructions illustrated may be effected by substituting different springs or by adjusting the position of the restraining nuts 20.

The advantages of the present invention arise from the provision of a condenser control which is entirely automatic in its operation and which is effective for positively 120 shutting off the supply of condensing water, or for restricting the same.

I claim:

1. In a condenser having an inlet pipe 125 for supplying condensing water thereto, a valve in said pipe responsive to pressures at the outlet thereof for controlling the flow of water therethrough, and a piston subjected on one side to atmospheric pressure and on 130

the other side to the pressure at the outlet of said valve for closing said valve as the pressure at the outlet increases, substantially as described.

- 5 2. In a condenser having an inlet pipe for supplying condensing water thereto, a valve in said pipe and a piston responsive to the difference in pressure between the atmosphere and that at the outlet of said valve
- 10 for closing said valve as the pressure at the outlet thereof increases, substantially as described.
- 15 3. In a condenser having an inlet pipe for supplying condensing water thereto, a pressure dissipating valve in said pipe, and a second valve in said pipe intermediate the first valve and the condenser responsive to pressures at the outlet of the second valve, substantially as described.
- 20 4. In a condenser having an inlet pipe for supplying condensing water thereto, a valve in said pipe responsive to pressures at the outlet thereof, and adjusting means for causing said valve to respond to definite pressures at said outlet, substantially as described.
- 25 5. In combination with a condenser, means for delivering condensing water thereto, an automatically operable valve for increasing or decreasing the effective flow of water through said means, actuating means for said valve subjected to an external and an internal pressure and movable to valve opening position upon a decrease in the internal pressure, means for varying the effective difference between said pressures, and means for controlling the speed of movement of said valve, substantially as described.
- 30 6. In combination with a condenser, means for delivering condensing water thereto, an automatically operable valve for increasing the effective flow of water through said means as the pressure at the outlet decreases, and decreasing the effective flow as the pressure at the outlet increases, and means for controlling the rate of movement of said valve, substantially as described.
- 35 7. In combination with a condenser, means for delivering condensing water thereto, an automatically operable valve for increasing

or decreasing the effective flow of water through said means, and means having a regulable movement for controlling the movement of said valve by variations in the pressure existing at the outlet thereof, said means being operable to close the valve as the pressure at the outlet increases, substantially as described.

8. In combination with a condenser, means for delivering water to the condenser, a valve for controlling the delivery of water to said means, and means subject indirectly only to the condenser pressure for opening and closing said valve respectively as the pressure in the condenser decreases and increases, substantially as described.

9. In combination with a condenser, means for delivering water to the condenser, a valve for controlling the delivery of water to said means, controllable means indirectly subject to the condenser pressure for gradually opening and closing said valve respectively as the pressure in the condenser decreases and increases, and a vacuum breaker for admitting air to the interior of said condenser, substantially as described.

10. In combination with a condenser, means for delivering condensing water thereto, a valve automatically operable in its opening and closing movements for controlling the supply of condensing water, said valve being responsive to variations in pressure at the outlet thereof for closing the valve as the pressure at the outlet increases, and means for controlling the speed of movement of said valve, substantially as described.

11. In combination with a condenser, means for delivering condensing water thereto, a valve automatically operable in its opening and closing movements for controlling the supply of condensing water to cut off the supply of water as the pressure in the condenser increases, and means for limiting the rate of movement of said valve, substantially as described.

In testimony whereof I have hereunto set my hand.

RAYMOND N. EHRHART.
